SAMUEL McCULLOCH, OF YELLOW SPRINGS, OHIO.

Letters Patent No. 72,063, dated December 10, 1867.

IMPROVEMENT IN CONVERTIBLE SHOT-GUN AND RIFLE.

The Schedule referred to in these Letters Patent and making part of the same.

TO WHOM IT MAY CONCERN:

Be it known that I, SAMUEL McCULLOCH, of Yellow Springs, Greene county, Ohio, have invented a new and useful Convertible Rifle and Shot-Gun; and I hereby declare the following to be a full, clear, and exact description thereof, reference being had to the accompanying drawings, making part of this specification.

This invention relates to a means by which the ordinary double-barrelled shot-gun may be converted into a combined rifle and shot-gun, for temporary or more extended use in that form. In the accompanying drawings—

Figure 1 is an axial section of the barrels of a double-barrelled shot-gun with my rifle-barrel inserted.

Figure 2 is a side elevation of the same.

Figure 3 is a square-ended plug-wrench, for introducing and removing the perforated plug shown in Figure 4.

Figure 5 shows my removable sight.

Figure 6 shows a modification of my rifle-barrel breech.

Figure 7 shows a modification of my method of affixing the breech-end into the rifle-barrel.

A and B are the right and left-hand barrels of a double-barrel shot-gun, and within the barrel A is inserted the rifle-barrel C, and retained in position by a screw-thread upon part D at the breech-end, the said end screwing into a suitable screw-threaded hole, E, at the inside end of a gun-barrel, the barrel being turned around by means of a key upon its hexagonal end c'.

The rifle-barrel C is furnished at suitable intervals with bands c, the band near the breech being much extended, so as to give strength and a good bearing to this barrel within the other. The rings or bands may be either shrunk on the barrel, or the general outside of the barrel may be turned down, leaving the rings projecting therefrom. The rifle-barrel has a general decreased diameter from breech to point, but the bands are all turned to the same diameter, so as to snugly fit the inside of the gun-barrel, to insure accuracy of fire, and to avoid the jarring of the one barrel within the other.

When the rifle-barrel is removed from the barrel A, a plug, F, seen in fig. 4, is screwed fast into the hole E, to decrease the breech-hole to the proper size, and to keep the screw-thread clean for use. The plug F is inserted and removed by means of a key, G, fig. 3, which traverses the whole length of the barrel, and is rectangular at the end, the plug-socket being of a suitable shape to receive the end of the key.

In the use of a rifle it is quite necessary to have a hind sight upon a gun, while in the use of the gun for shot only it is almost as imperative that there should be no hind sight, as the gun has to be brought quickly up to the eye without the necessity of such extreme accuracy as that required in shooting ball. In shooting at the game when the same is moving on leg or wing, the sportsman prefers to take sight over the concave breech of the gun, without the intervention of any object between that and the end sight; so that in a convertible rifle and shot-gun it is demanded that the hind sight should be removable. In view of this, I provide a sight which may be removed at pleasure by the withdrawal of a screw. My hind sight (see fig. 5) is formed of two pieces, H and I, the lower piece, H, being grooved at h to fit the upper side of strip J, which connects the two barrels together, and held fast to said strip by a screw, h'. The piece H is also grooved transversely on the upper side, for the reception of the cross-piece I. The piece I is furnished with two notches, i i', one of which is appropriate to each barrel. In the use of a single hind sight on a double-barrel gun, perfect accuracy of aim is not attainable, as the line of fire must cross the line of sight at some single point, whereas the lines of sight from the two notches i i', and the end sight j, each forms a nearly perfect guide for aim to its appropriate barrel. The piece I admits of side adjustment in its groove in the plate H.

One manner of placing the breech-piece D D' in my rifle-barrel is seen in fig. 1, where the inside of the bore is sufficiently enlarged, and screw-threaded at its rear, to admit of screwing in the said piece a requisite distance, and leaving a sufficiency of its length projecting to form the part D, to screw fast into the hole E of the gun-breech, as before mentioned. In fig. 6 is shown a modification of the breech-screw D, in which the said screw is formed on a diminished part of the barrel proper. In fig. 7 is shown my preferred form of placing the breech-piece D D' in the rifle-barrel, in which the breech is formed of a separate piece, of the same outside diameter as the inside of gun-barrel A, the said piece being furnished with a screw-thread on each end, the screw D to enter the hole E, and the screw D' to attach the said breech to the rest of the barrel by screwing

fast into a suitable screw-threaded opening. This breech-piece has flattened places on it, to enable its insertion or removal by an appropriate key.

In applying my improvement to a common shot-gun, which can easily be done, the rifle-barrel being turned to the proper size, might be used as a socket for the drill, to guide the said drill, used in drilling the hole E, to its proper starting-place, and restrict it to its right course.

This convertible gun is much better than a gun made with one shot and one rifle-barrel, as the latter cannot be used with any satisfaction or success in shooting game upon the wing. The removal of my rifle-barrel and hind sight, and the insertion of the plug F, restores the gun to the usual form of a shot-gun in all respects. The rifle-barrel C, in most cases, is entered into and removed from the muzzle of the barrel A; but in case the improvement is to be applied to an old gun that is much enlarged or burned out at the breech, and it is desired to use as large ball as possible, the breech of the shot-barrel is taken out, the bore is trued a little to make it perfectly round, the rifle-barrel is turned to fit, and slipped in from the breech-end of the gun; the shot-barrel breech is then screwed in, and the key can be used on the point of the rifle-barrel, backward or forward, to make the shoulders come up tight, and both together. The rifle-barrel, in this case, is removed in the same way, by taking out the shot-barrel breech-pin.

I claim herein as new, and of my invention—

1. The removable barrel C, constructed with external collars e, and secured within a shot-gun barrel, A, by a screw, D, substantially as and for the purposes set forth.
2. I claim the plug F, for the purposes set forth.

In testimony of which invention, I hereunto set my hand.

SAMUEL McCULLOCH.
